UNITED STATES PATENT OFFICE.

WILLIAM B. PLACE, OF KING'S MILLS, OHIO, ASSIGNOR TO THE PETERS CARTRIDGE COMPANY, OF CINCINNATI, OHIO.

MACHINE FOR PRIMING OR CAPPING HEADS OF CARTRIDGE-SHELLS.

SPECIFICATION forming part of Letters Patent No. 605,339, dated June 7, 1898.

Application filed March 26, 1894. Serial No. 505,203. (No model.)

To all whom it may concern:

Be it known that I, WILLIAM B. PLACE, a citizen of the United States, residing at King's Mills, in the county of Warren and State of Ohio, have invented a new and useful Machine for Priming or Capping the Heads of Cartridge-Shells, of which the following is a specification.

This invention relates to machinery for use in the manufacture of shells for cartridges, and it has for its object the provision of mechanism for automatically priming the cartridge-shell.

With this object in view the invention consists in the provision of improved mechanism for feeding the caps or primers to the cartridge-shell and setting the same in place.

The invention also consists in the various constructions, location, and relative arrangements hereinafter more particularly described, as shown in the accompanying drawings, and finally pointed out in the appended claims.

Reference is now had to the accompanying drawings, forming a part hereof, and to the several views and reference-signs appearing thereon, wherein—

Figure 1 is a view in front elevation of my entire machine. Fig. 2 is a side elevation of the same, looking from the left of Fig. 1. Fig. 3 is a horizontal sectional view taken on the line $\alpha\alpha$, Fig. 2. Fig. 4 is a vertical sectional view taken on the line yy , Fig. 3. Fig. 5 is a detailed plan view of the mechanism for delivering the caps or primers to the cap-setting die, the feed-chute being shown in horizontal section and parts being broken away. Fig. 6 is a front view of the mechanism shown in Fig. 5. Fig. 7 is a detailed view, in vertical section, of the lower end of the cap-feeding chute. Fig. 8 is a front detail view of the feeding-chute detached from the machine. Fig. 9 is a vertical section of the same, taken on the line zz , Fig. 8. Fig. 10 is a detail view, in vertical section, of the shell-extracting device.

Similar reference-signs refer to and designate similar parts wherever they occur throughout the several views.

50 A designates a table or base-plate, which

may be suitably supported in any convenient way.

Bolted or otherwise suitably secured to table A and rising therefrom are two uprights or standards B and C. In the upper ends of standards B and C is journaled in suitable bearings the main drive-shaft D, having a drive-wheel E mounted thereon, adapted to receive rotary motion from any suitable source of power and to transmit the same through shaft D to the various mechanisms hereinafter described. Any suitable form of clutch mechanism, as indicated at F, may be employed for clutching or unclutching drive-wheel E from the shaft D, and this clutch may be operated in any suitable and ordinary way, as by a foot-treadle (not shown) located convenient to the foot of the operator and connected by rod G to the clutch mechanism F, as will be readily understood.

Intermediate its bearings shaft D is formed into a crank-arm H. A pitman I is attached to crank H and is pivoted to a plunger-head J, adapted to be reciprocated in suitable guideways 1 and 2, formed in or bolted to the inner edges of standard B and C. Plunger-head J carries the shell-eveener, the head-perforator, the cap or primer setting die, and the shell-extractor, as will more fully hereinafter appear.

I will now describe the mechanism for feeding and properly presenting the shells to the several mechanisms by which the cap or primer is supplied to the head. Reference numeral 3 designates a circular plate provided with a series of equally-spaced screw-threaded perforations or sockets, as at 4, Fig. 4, through the outer edge thereof. Shell-supporting pins 5, screw-threaded on their lower ends, are adapted to be received in said screw-threaded sockets. By this construction it will be seen that the shell-supporting pins can be readily and easily inserted or removed from the sockets 4 and can also be readily adjusted as to height, as may be desired. Check-nuts 6 serve to hold said pins rigidly in place. Pins 5 are of a size and length to receive thereon and snugly fit inside the open end of a shell 7, as will be readily understood, and said pins are each provided with a central longitudinal

channel or bore 8, which may extend throughout the length thereof and which is larger at the base of the pin than at the end, for a purpose presently to be described. Table A is provided with a hub 9 in the front part thereof, (see Fig. 4,) adapted to receive in a perforation therein a shouldered pin 10, the shoulder resting upon the top surface of the table and adapted to be received in a central perforation in carrier disk or plate 3. Pin 10 is screw-threaded upon its upper end and is adapted to receive thereon nuts 11 and 12, which by means of suitable washers 13 serve to clamp carrier disk or plate 3 against the top surface of table A tight enough to afford frictional resistance against rotation until positively moved or rotated. Ratchet-teeth 14 are formed in the base-flange of carrier-plate 3, which teeth are adapted to be engaged by a pawl 15, which is reciprocated and is held in engagement with the ratchet-teeth 14 by means of a spring 16. Pawl 15 is reciprocated by means of the following - described mechanism: Upon the end of shaft D opposite the end upon which drive-wheel E is located is mounted a disk 17, having a pin 18, adapted to be received in slot 19 in the end of a lever 20, pivoted intermediate its ends, as at 21, to standard B. The opposite end of lever 20 is pivoted, as at 22, to a link 23, which is in turn pivoted, as at 24, to a block 25, adapted to slide in suitable guideways 26 27, formed in or bolted to casting or standard B. Pawl 15 is pivoted to the front end of slide-block 25. It will be seen from the construction just described that the rotation of main shaft D causes lever 20 to oscillate or rock, and this rocking rotation is translated into a reciprocating motion by means of link 23 and the pivoted connections thereof, thus effecting the reciprocation of slide-block 25 and pawl 15. This reciprocation of pawl 15 imparts a step-by-step positive feed to the shell-carrier in order to present the shell successively to the action of the evener, head-perforator, cap-setter, and shell-extractor.

I will now describe the various devices to which a shell is successively presented by the carrier. The shells which have been previously supplied with heads are placed by an operator upon the pin-supports in the shell-carrier. The step-by-step feed of said carrier first presents the pin carrying the shell to the evener. This is a headed rod 28, adjustably supported in a sleeve carried by plunger-head J, and serves to force the shells as successively presented to it down upon their supporting-pins to a uniform distance, or preferably until the inner face of the head rests solidly against the upper end of the pin-support. Further rotation of the carrier presents the leveled and evened shell to the action of the perforator. This comprises a punch 29, adjustably held in a socket in the plunger-head, and it operates, in connection with the central longitudinal perforation 8 in

the shell-supporting pin, as a die to punch out a hole in the head to receive the cap or primer. The part punched out falls down through perforation or bore 8 in the pin and through a perforation 30 in table A. (See Fig. 4.) The shell is next presented to the cap or primer placing mechanism, presently to be described, and the action of the setting-die 31. This die is adjustably held in a socket in plunger-head J and is shaped on the lower end thereof to conform to the shape of the face of a cap or primer and serves to force a cap firmly into the seat prepared for it in the shell-head, as will be readily understood by reference to Fig. 4 of the drawings. The capped shell is next presented to the extracting device 32. This comprises a sleeve adjustably supported by plunger-head J, provided with an enlarged head which has two oppositely - inclined passages 33 33 therein, adapted to receive blocks 34 34 therein, beveled on their meeting faces and provided with hooks or shoulders, as shown in Fig. 10. These blocks are loosely mounted to slide in said passages and are prevented from falling out when not in action by adjustable bolts 35 35, as clearly shown. When plunger-head J is reciprocated, the lower ends of blocks 34 34 strike the head and are forced upwardly by reason of the inclination given to the passages or chambers which contain said blocks. The lower ends thereof are forced apart until they finally drop over the rim of the head, and they drop by gravity into position for the hooks or shoulders thereon to engage the head, and when the plunger-head moves in the opposite direction the shell 7 is extracted from its supporting-pin and held suspended by its head, as shown in Fig. 10. Upon the next reciprocation of plunger-head J the shell held suspended by its head is forced up into the sleeve by its lower end coming in contact with the head of the next succeeding shell, and so on upon each reciprocation of plunger-head J, until finally the shell is forced out through the upper end of said sleeve, where it strikes an inclined mouthpiece 36', which deflects it into a suitable funnel, whence it falls into a suitable receptacle. The caps or primers are delivered in a single row to the placing device by means of a feeding-chute, which I designate generally by reference-sign K. This chute comprises a stationary part 36 and a removable part 37. The stationary part is preferably formed into an enlarged chamber 38, adapted to receive therein an agitating device, such as plate or disk 39, having a pin 40 in the face thereof, (see Fig. 8,) by means of which the caps or primers are forced singly into a raceway or channel 41, communicating with the enlarged chamber at the lower part thereof. This raceway is curved at its lower end (see Fig. 7) in order to deliver the caps properly upon a horizontal table, presently to be described. The agitating-disk 39 is rocked or oscillated by means of a crank-arm 42, which

has a perforated flange 43 thereon, adapted to receive therethrough a rod 44, which is provided with adjustable collars 45 46. Interposed between said collars and perforated flange 43 on either side of the latter and coiled about rod 44 are two springs 47 48. Rod 44 is reciprocated by means of a pin on a crank-arm 49 on the end of a shaft 50, journaled in suitable bearings in the rear part of the machine. Rotary motion is imparted to shaft 50 from main driving-shaft D by means of a suitable gearing, such as belt 51, which passes around pulley 52 on shaft D and a pulley 53 on shaft 50. By this construction it will be seen that agitating-disk 39 is rocked or oscillated yieldingly upon each revolution of main shaft D.

I will now describe the mechanism for placing the caps or primers in position to be set in the shell-head. A circular horizontally-arranged table 54 is mounted to rotate upon a vertical support adjustably mounted in hub 56, bolted or otherwise secured to table A. Table 54 in the form shown is grooved in the outer periphery thereof and is adapted to receive therein a belt 57, which also passes around a pulley 58 on shaft 50. (See Fig. 3.) Any other suitable means may be employed to continuously rotate table 54. The caps are delivered to table 54 by raceway 41 in a single row, the lower end of said raceway being curved to properly deliver the same thereto, as clearly shown in Fig. 7. Upon the upper end of support 55 is rigidly held a plate 59 in close proximity to the upper face of table 54. Plate 59 is provided with a groove 60, adapted to receive the single row of caps as they are delivered to table 54 from raceway 41 and to guide the caps while being fed by rotating table or feed-plate 54 to the point where they are fed singly into position to be seated in a shell-head. (See Fig. 5.) The mechanism for accomplishing this end will now be described.

Disk 17, hereinabove mentioned, is eccentrically mounted on shaft D and is provided with a strap 61, having a short arm or pitman 62. A lever 63, pivoted intermediate to its ends, as at 64, to standard B, is pivoted at its upper end to a pin 65, carried by pitman 62. The lower end of lever 63 is slotted, as at 66. A pin 67, carried by crank-arm 68, is adapted to work in said slot. Crank-arm 68 is sleeved on a short shaft 69, journaled in suitable bearings in standard B. A crank-arm 70, slotted, as at 71, is carried by the other end of the shaft 69. A pin 72, carried by a link 73, is adapted to be received in slot 71. (See Figs. 2, 3, and 4.) Pin 72 is connected by link 73 to a slide-bar 75, adapted to slide in suitable guideways in plate 59. Plate 59 is cut away, as indicated at 76, Figs. 3, 4, and 5, and in this cut-away portion is adapted to reciprocate a head-block 77, carried by slide-bar 75. To head-block 77 is attached a plate 78, adapted to slide in close proximity to the wall 79 of cut-away portion 76 of plate 54. The outer portion of plate 78 is grooved or cut away to

conform to the shape of a cap or primer and is adapted to receive therein as one jaw of a clamp the primers as they are delivered into the path of reciprocation thereof from the groove 60 in plate 59 by table or feed-plate 54, as clearly shown in Fig. 5. The other jaw 80 of the clamp is pivoted, as at 81, to head 77 and is grooved correspondingly to the corner of plate 78 in order to firmly grasp and securely hold a cap between said jaws. A spring 82 is attached to one end of pivoted jaw 80 and at the opposite end to plate 78 and tends to keep said jaw constantly closed upon the end of plate 78. The end of pivoted jaw 80 projects over the corner of plate 59, so that when head 77, carrying the clamping-plate and spring-jaw, reciprocates rearwardly the projected end of said pivoted jaw comes in contact with the corner of the plate 59 before the end of the rearward reciprocation is reached, thus opening the clamp against the action of spring 82. In feeding such small articles as cartridge caps or primers it sometimes happens that the caps are not fed completely beyond the mouth of the groove 60. In such case when clamp-plate 78 is projected forwardly to place the cap in position to be set in the cartridge-head the cap is bent or injured by coming into contact with the edge or outer wall of groove 60. In order to obviate this injury and to remove this objection, I cut away the outer wall of groove 60, as clearly shown at 83, Fig. 6, and place therein a lug or tongue 84, carried by a leaf-spring 85. Therefore when a cap becomes wedged between clamp-plate 78 and the outer wall of the feeding-groove said wall will yield, thus permitting the clamping-plate to grasp and hold a cap and project the same into position to be set by the setting-die without injury to the cap. The operation of this part of my machine is as follows: Main shaft D is being constantly rotated, and its rotary motion is communicated to the cap-feeding table by gearing 51 57 and intermediate shaft 50. The caps are delivered to said feeding-table in a single row and are fed thereby to the point where they are grasped singly by the clamp and projected into position to be acted on by the cap-setting die. Lever 63 is rocked or oscillated by means of eccentric 17, and its rocking motion is communicated to rock-shaft 69, which by means of pivoted link 73 reciprocates slide-bar 75 and the cap-clamp. The several mechanisms are so timed as to impart to the clamp one complete reciprocation during each reciprocation of plunger-head J.

In order to prevent the perforating-die 29 from withdrawing the shell from its supporting-pin, I provide a perforated plate 86, said perforating-die operating through the perforation in said plate 86, which thus acts as a stripping-plate, which will be readily understood.

It is obvious that many changes and alterations may be made in the details of construction and arrangement without departing from

the spirit or scope of my invention. I do not limit myself, therefore, to the exact details shown and described.

I am aware of the application for a patent 5 filed April 5, 1897, Serial No. 630,750, for wad-placing mechanism in cartridge-loading machines by Gersham Moore Peters, and I wish it to be understood that I do not herein claim anything which will conflict with the subject-10 matter claimed in the said Peters application..

Having now fully, clearly, and concisely set forth a preferred form of my invention and its mode of operation, what I claim as my invention, and desire to secure by Letters Patent of the United States, is—

1. In a machine of the class described, a rotating cap-feeding table, a feed-chute, means for delivering the caps from said chute to said 20 table in a single column, and a reciprocating device for feeding the caps singly from the end of said column upon said table, and placing them in position to be inserted in a head, as and for the purpose set forth.

2. In a machine of the class described, a cap-feeding table horizontally arranged and provided with a groove, a vertical feeding-chute arranged to deliver the caps upon said table and into said groove in a single column, and 30 reciprocating placing mechanism, as and for the purpose set forth.

3. In a machine of the class described, a rotating cap-feeding table, a grooved plate, a feed-chute arranged to deliver the caps to said 35 table and within the groove in said plate, and reciprocating placing mechanism, as and for the purpose set forth.

4. In a machine of the class described, a cap-feeding table, a cap-feeding chute arranged 40 to deliver the caps upon said table in a single column, a cap-placing mechanism comprising a head having clamping-jaws, one of said jaws being pivoted thereto, and means for reciprocating said head transversely the 45 column of caps upon said table, said pivoted clamping-jaw having a prolonged end whereby said jaws are opened to receive a cap, as and for the purpose set forth.

5. In a machine of the class described, cap 50 feeding and placing mechanism comprising a continuously-rotating table, a stationary grooved plate, and a head having clamping-jaws adapted to reciprocate across the top of said table and transverse to the groove in said 55 plate, and means for delivering the caps singly to said table and within said groove, as and for the purpose set forth.

6. In a machine of the class described, a stationary grooved feeding-plate provided with 60 a yielding part in the wall of said groove, as and for the purpose set forth.

7. In a machine of the class described, a stationary grooved feeding-plate having a portion of the wall of said groove cut away, in 65 combination with a spring-supported lip or tongue adapted to be received in said cut-away portion as and for the purpose set forth.

8. In a machine of the class described, a cap-placing device comprising a head, a plate secured to said head and grooved or cut away in one of the projecting corners thereof, a spring-pressed jaw pivoted to said head, said jaw provided with an extended end and also grooved to correspond with the groove in said plate and adapted to form therewith a clamp, 75 and means for reciprocating said head, and means adapted to engage the extended end of said pivoted jaw at the limit of movement of said head, whereby it is rocked about its pivot to open said jaws, as and for the purpose set forth.

9. In a machine of the class described, a main driving-shaft, a rotary eccentric mounted thereon, a reciprocating cap-placing clamp and means operated by said eccentric for reciprocating said clamp, as and for the purpose set forth.

10. In a machine of the class described, a main driving-shaft, an eccentric and strap mounted thereon, a lever pivoted intermediate its ends and connected at one end to said strap, a cap-placing clamp and means operated by the other end of said lever for reciprocating said clamp, as and for the purpose set forth.

11. In a machine of the class described, a rock-shaft, a slotted crank-arm carried thereby, a cap-placing clamp, a link pivoted at one end to the clamp and at the other end attached to said slotted crank-arm, and means for rocking said rock-shaft, whereby said clamp is reciprocated, as and for the purpose set forth.

12. In a machine of the class described, a feeding-chute having an enlarged chamber, a cap-agitating disk arranged in said chamber 105 having a flanged crank-arm connected to the hub thereof, a rod adapted to pass through a perforation in said flange and having collars, springs interposed between said flange and collars, and means for reciprocating said rod 110 comprising a rotating shaft and a crank-arm thereon, all combined and arranged as and for the purpose set forth.

13. In a machine of the class described, the combination with a table having a perforation therethrough, of a punch arranged to operate in line with said perforation, and a shell-supporting pin adapted to present the shells to the action of said punch, said pin provided with a central longitudinal bore therethrough 120 increasing in size from one end to the other, as and for the purpose set forth.

14. In a machine of the class described, a shell-feeding disk provided with suitably-spaced screw-threaded perforations through 125 the outer rim thereof, and longitudinally-bored shell-supporting pins screw-threaded at the lower end, to be received in said screw-threaded sockets, as and for the purpose set forth.

15. In a machine of the class described, a feeding-chute, an agitating-disk arranged therein, a flanged crank-arm connected to said disk, a rod arranged to pass through a

perforation in said flange, means for reciprocating said rod and springs interposed between said rod and flange, as and for the purpose set forth.

5 16. In a machine of the class described, a cap-feeding device comprising a table, means for delivering the caps thereto in a single column, a reciprocating clamp having a pivoted jaw adapted to grasp the caps singly from the 10 end of said column, and to place them in position to be inserted in a shell, and connections for reciprocating said clamp, as and for the purpose set forth.

17. In a machine of the class described, a 15 main driving-shaft, a reciprocating cap-feeding device comprising a clamp having a piv-

oted jaw, means for reciprocating said device from said shaft, a cap-feeding chute arranged to deliver the caps to said feeding device in a single column, means actuated by said main shaft for feeding the caps singly down said chute, and means whereby the pivoted jaw of said clamp is opened at one limit of movement of said clamp to receive a cap therein, as and for the purpose set forth. 20

In witness whereof I have hereunto set my hand, this the 10th day of March, 1894, in the presence of two subscribing witnesses.

25 WILLIAM B. PLACE.
